TELESCOPING MEMBERS AND LATCH MEANS THEREFOR

Henricus F. J. Bernaerts, Weert, Netherlands

Application January 22, 1951, Serial No. 207,132

Claims priority, application Netherlands February 4, 1950

4 Claims. (Cl. 188—67)

The present invention relates to a hydraulic lifting jack with a lifting column in general and to a lifting member in particular, which lifting jack is preferably used for lifting heavy loads, e. g. aircraft.

Since most of the known devices of this type are operated by means of a hydraulic system or by compressed air, the devices of this kind may cause accidents in case of faults of the pressure system working on the lifting member. Such faults are particularly dangerous when lifting aircraft, for, when in the lifting position of an aircraft, the lifting member fails and the aircraft drops, internal fractures of the fuselage or the wings may be caused. Therefore, in such lifting jacks it is of the greatest importance that faults in the pressure system never lead to a sudden lowering of the lifting member.

In order to avoid the dangerous sudden lowering of the lifting member it has been proposed before to provide a lifting member with teeth which cooperate with one or more latches, the ends of which engage the teeth of the lifting member and, thereby, are retained in lifted position. It was, however, characteristic for all known structures that the latches had to carry the full load since forces parallel to the longitudinal axis of the lifting member did bear on the ends of the latches engaging the teeth of the lifting member. It was, of course, necessary to provide teeth of comparatively large dimensions in order to provide sufficient bearing surface, since the teeth alone had to carry the heavy load.

It is, therefore, one object of the present invention to provide a structure comprising a lifting member having teeth disposed longitudinally at its outer face, which teeth cooperate with the inner end of one or more latches, the axis of which latches, however, forms an acute angle with the longitudinal axis of the lifting member, in order to provide an important pressure component perpendicularly to the surface of the lifting member, the latches, thereby, operating as clamping members, which operation decreases to a great extent the possibility of shearing of the teeth on the lifting member.

It is another object of the present invention to provide a structure comprising a lifting member having teeth longitudinally disposed on its outer face, which teeth cooperate with one or more latches, in which the latches may be unlocked by means of a cam ring, the latter including means for rendering the same operative only when the pressure system is functioning, so that an unlocking of the latches is not possible when the pressure system is out of order.

It is another object of the present invention to provide a structure comprising a lifting member having teeth longitudinally disposed on its outer face, which teeth cooperate with one or more latches, the latter being moved into inoperative lifting position by means of a cam ring to which resilient means are connected to return the cam ring automatically into the position in which the latches are in operative locking position.

It is yet another object of the present invention to provide a structure comprising a lifting member having teeth longitudinally disposed on its outer face, which teeth cooperate with one or more latches, the latter being moved into inoperative lifting position by means of a cam ring and the pressure operated lifting member may be lowered by means of a regulating valve, and in which the cam ring for lifting the latches and the handle for operation of the regulating valve are mutually locked in such manner that the cam ring can only be rotated in the closed position of the regulating valve and that the regulating valve can only be opened when the cam ring assumes the position in

2

which the latches are in their inoperative lifting position.

With these and other objects in view which will become apparent in the following detailed description, the present invention will be clearly understood in connection with the accompanying drawing, in which:

Fig. 1 gives a view in elevation, partly in section, of a lifting jack according to the invention.

Fig. 2 gives a section of one of the latches with a part of the lifting ram.

Fig. 3 gives a transverse section taken along the line 3—3 of Fig. 1.

Fig. 4 gives an end view on the latch mechanism.

Fig. 5 shows the construction of the regulating valve.

The lifting jack consists of a central column with outer wall 1, said wall being provided with lugs 2, 2' and 3. The lugs are connected with legs 4 carrying at their lower end footplates 5, struts 6 being provided between the lugs 3 and the legs 4. The legs 4 may be connected with the lugs 2' instead of with the lugs 2 in which case the struts 6 are placed in a downward position.

The column comprises an outer wall 1 and an inner pressure cylinder 8, the sump 9 for the hydraulic fluid being provided between these walls. A hydraulic fluid, preferably an oil, is used. The oil from the sump 9 may be pumped into the chamber 10 of the cylinder 8 under the piston 11 of the lifting ram 12 by means of a pumping system arranged in the bottom 13 of the column, which bottom 13 carries channels therein (not shown). The piston 14 of the pumping system is actuated by means of a bell cranked lever 16, 16' with a pivot 15 and a handle 17.

The piston 11 carries two packing collars 18, 19, the collar 19 functioning as a security against oil leaking along the collar 18. At the upper end the lifting ram 12 carries an insert 20 provided with a screw thread engaging a screw spindle 21 with bearing head 22 and lock nut 23. The spindle 21 may be locked with respect to the ram by means of the nut 23.

In order to avoid the spindle 21 from becoming unscrewed too far with respect to the insert 20 the lower end of this spindle carries a pivoting pawl 24, said pawl striking against the lower end of the insert 20 when the spindle 21 is screwed upwards. When the lifting jack is turned upside down, the pawl 24 turns in the direction of the arrow X thus enabling complete removal of the spindle 21.

The central column consisting of the cylindrical parts 1 and 8 is closed at the upper end by means of an annular cover 25 containing a cotter 26 engaging a slot of the lifting ram 12 and thus preventing rotation of the ram.

The outer surface of the lifting ram 12 is provided with engraved teeth 27, 28 each extending about a quarter of the periphery. These teeth 27, 28 cooperate with latches 29, 30, said latches being mounted opposite the teeth 27, 28 of the lifting ram 12 and carried by pivot pins 31 inserted into wide bores of the latches. Plate springs 32, 33 are pressed against the latches.

By a reciprocating movement of the handle 17 oil is pumped into the chamber 10 by means of the pumping system in the bottom 13 so that the lifting ram 12 is lifted. The teeth 27, 28 pass the latches 29, 30 during the lifting movement.

In case of a sudden decrease of the hydraulic pressure which might cause lowering of the ram, the latches 29, 30 engage the corresponding teeth 27, 28 and the weight of the load is taken up by the latches 29, 30. These latches rest with rounded parts 34 in bowl shaped recesses 35 of the column.

Unlocking of the latches is only possible when the piston 11 is again under hydraulic pressure. To this end it is necessary to lift the ram 12 for a distance of a few millimeters, so that the latches are unlocked with respect to the teeth. Now it is possible to turn the latches by means of the cam ring 36 which may be rotated by means of a handle 37 of the ring against the action of a spring 48, said spring being connected between the cam ring 36 and the cover 25. The cam ring 36 is locked against axial shifting by means of two locking plates 50, 51 connected to the cover 25 by means of screws 53.

The lifting ram 12 can now be lowered by releasing the oil from the chamber 10 into the sump 9 through the

passage 38 in the bottom 13 by means of the regulating valve of Fig. 5.

The regulating valve consists of a needle valve 39 cooperating with a fixed seat in the bottom 13 of the column; this needle valve is carried by a screw spindle 40. This screw spindle engages a nut 41 which may be turned after removal of a cover 42 functioning as locking means for the adjustment of the needle valve 39. The extension 43 of the screw spindle 40 carries at its upper end a handle 44 and is pressed upwards by means of a pressure spring 45. In this way the handle 44 can take up the same position in closed position of the needle valve even after wear of needle and seat in view of the fact, that the nut 41 may be adjusted.

This is of importance in view of the mutual locking of the cam ring 36 and the spindle 43. The needle valve 39 can only be opened by turning the handle 44 in the direction of the arrow Z after the recess 46 of the cam ring is adjusted in front of a corresponding cam 47 of the screw spindle 43, that means that after the cam ring 36 has been turned over an angle of about 90° in the direction of the arrow Y with respect to the position of Fig. 4.

In the open position of the needle valve 39 the cam ring 36 is locked. After returning the handle 44 of the needle valve from the open into the closed position as indicated in Fig. 4 the cam ring 36 is released by the part 47 and the ring 36 is returned under the action of the spring 48 in the position of Fig. 4 in which the latches 29, 30 return in the locked position.

While I have disclosed one embodiment of the present invention, it is to be understood that this embodiment is given by example only and not in a limiting sense, the scope of the invention being determined by the objects and the claims.

What I claim is:

1. In a lifting jack, the combination of a vertically disposed frame including a hollow fixed part and a longitudinal member extending throughout and past the fixed part and mounted for movement in axial direction therein, a part of the periphery of the said longitudinal member having teeth disposed longitudinally thereon, a plurality of clamping members disposed around and pivotally mounted on the said fixed part, each of said clamping members extending upwardly from its pivot point toward the said longitudinal member at an acute angle to a plane extending through the said pivot point perpendicularly to the longitudinal axis of the said movable member, when in clamping position, the inner ends of the said clamping members engaging the teeth of the said longitudinal member, to lock the latter in any position by clamping action as the result of a pressure component perpendicularly to the longitudinal axis of the longitudinal member.

2. In a lifting jack, the combination of a vertically disposed frame including a hollow fixed part and a plunger

extending throughout and past the fixed part and mounted for movement in axial direction therein, a part of the periphery of the said plunger having teeth disposed longitudinally thereon, a plurality of latches disposed around and pivotally mounted on the said fixed part, each of said latches extending upwardly from its pivot point toward the said plunger at an acute angle to a plane extending through the said pivot point perpendicularly to the longitudinal axis of the said plunger, when in latched position, the inner faces of the said latches having teeth complementary to the said teeth of the plunger, to lock the said plunger in any position by clamping action as the result of a pressure component perpendicularly to the longitudinal axis of the plunger.

3. In a lifting jack, the combination of a vertically disposed frame including a hollow fixed part and a plunger extending throughout and past the fixed part and mounted for movement in axial direction therein, a part of the periphery of the said plunger having teeth disposed longitudinally thereon, a plurality of latches disposed around and mounted on the said fixed part, each of said latches extending upwardly from its pivot point toward the said plunger at an acute angle to a plane extending through the said pivot point perpendicularly to the longitudinal axis of the said plunger, when in latched position, the said plunger having bowl-shaped recesses equal in number to that of the said latches and the latter resting in the said bowl-shaped recesses for angular movement, to lock the said plunger in any position by clamping action as the result of a pressure component which extends perpendicularly to the longitudinal axis of the said plunger and is taken up by the inner face of the said recesses of the said fixed part.

4. The lifting jack, as set forth in claim 3, which includes a cam-operated means rotatably secured to the said fixed part for maintaining the said latches in lifted inoperative position.
